UNITED STATES PATENT OFFICE.

ALBERT HUNTER, OF PORTLAND, OREGON.

HOLDER-ON.

1,323,059. 1918.21A

Specification of Letters Patent. Patented Nov. 25, 1919.

Application filed May 6, 1919. Serial No. 295,228.

To all whom it may concern:

Be it known that I, ALBERT HUNTER, a citizen of the United States, residing at Portland, in the county of Multnomah and

5 State of Oregon, have invented certain new and useful Improvements in Holders-On, of which the following is a specification.

The present invention relates to improvements in holders-on for pneumatic tools or 10 riveting machines, designed for the purpose of backing up the rivets when driven by long stroke hammers of well known type, and the subject matter of the present invention, although not confined solely for the 15 purpose, is specifically adaptable for use in ship construction when operating on the metal plates of the hull and other portions of the vessel.

The invention consists essentially in the 20 novel combinations and arrangements with the riveting machine or pneumatic tool of the alined, extensible holder-on that is adjustable to suit the space between the part to be riveted and a fixed or stationary element against which the holder-on may be 25 placed to back up the tool in its movements.

In the accompanying drawings one complete example of the physical embodiment 30 of the invention is illustrated the parts being constructed and combined according to the best mode so far devised for the practical application of the principles of the invention.

Figure 1 is a side view, in elevation, of a 35 riveting machine or pneumatic tool equipped with the holder-on of the present invention.

Fig. 2 is an enlarged, detail view, partly 40 broken away for convenience of illustration, of the invention as embodied in the device to be described.

In order to fully illustrate the invention I have depicted in the drawings a standard 45 form of center piston type riveting machine or pneumatic holder-on 1 equipped with the usual air connection 2, which includes the threaded tapered thimble 3 by means of which the holder-on is attached to the machine.

The device of the invention includes a 50 rack bar 4, of suitable dimensions and weight, that is screw threaded at one end to be entered and secured in the complementary thimble 3 of the riveting machine, and the device also includes the extension bar 5 55 that telescopes over the rack bar and is adjustable thereon longitudinally and guided

and held against rotation thereon by means of the surface groove 6 in the rack bar and the screw or bolt 7 in the telescopic extension bar.

The extension bar is preferably a hollow or tubular member, as a metallic pipe and is 60 slidable, within the limits of the groove 6, on the rack bar, and adjustable thereon through the instrumentality of the pivoted pawl 8 movable in the ears 9 of the fixed band 9' on the extension bar 5, and this pawl is normally held in engagement with the rack bar by the spring 10 between the handle 10' of the pawl and the extension bar 5. 65 The extension bar is equipped with the usual tool point 11 held fixed by the set bolt 12.

In Fig. 1 the invention is illustrated in 70 position for use on a ship's bottom, the holder-on being supported by the block 13, and the implement being arranged for use in vertical position so that the hammer 14 of the tool is alined with the extension device or holder-on of the tool. Where the 75 necessity for using the tool in horizontal position arises, the tool is backed up against bracing or against the timbers of the ship-way.

The extensible holder-on is adjusted approximately to the space to be occupied, and of course provision is made for the reciprocation of the riveting tool or head, and it will readily be apparent that the extension 80 holder-on, when in proper position will perform the function of backing up the tool 85 with efficiency and satisfaction.

From the above description taken in connection with the drawings, it is evident that I have provided a device that fulfils the 90 conditions of a comparatively perfect holder-on for this purpose, as embodied in the following claims.

Having thus fully described my invention, what I claim as new and desire to secure by Letters Patent is—

1. The combination with the riveting tool and its alined rack bar, of a hollow extension bar on said rack bar, means for preventing relative rotary movement of the bars, 105 and a pivoted pawl on the extension bar engaging the rack bar for retaining the bars in adjusted position.

2. The combination with the riveting tool and its alined, longitudinally grooved, rack 110 bar, of a telescoping bar having a screw extending in the groove and provided with a

pivoted pawl engaging the rack bar, as described.

3. The combination with the riveting tool and its alined rack bar, of a hollow extension bar on said rack bar, means for preventing relative rotary movement of the bars, a pivoted pawl on the extension bar

engaging the rack bar for retaining the bars in adjusted position, a tool point extending from the extension bar, and means for adjustably supporting same therein. 10

In testimony whereof I affix my signature.

ALBERT HUNTER.
